UNITED STATES PATENT OFFICE.

JAMES W. NANCE, OF TWIN FALLS, IDAHO, ASSIGNOR OF ONE-FOURTH TO HUBERT W. WILSON, OF TWIN FALLS, IDAHO.

SPARK-PLUG.

1,073,699.

specification of Letters Patent. Patented Sept. 23, 1913.

Application filed June 5, 1911, Serial No. 631,210. Renewed February 17, 1913. Serial No. 749,031.

To all whom it may concern:

Be it known that I, JAMES W. NANCE, a citizen of the United States, residing at Twin Falls, in the county of Twin Falls and 5 State of Idaho, have invented certain new and useful Improvements in Spark-Plugs, of which the following is a specification, reference being had to the accompanying drawings.

10 My invention relates to new and useful improvements in spark plugs and my object is to provide a device of this character which is in every way superior to and is adapted to supersede the spark plugs now in use.

15 A further object of the invention resides in providing a plug in which the amount of spark given therefrom will be increased with the same amount of current being applied, which increasing of spark will increase the 20 power of the engine to which the same is applied.

25 A still further object resides in providing a plug with a pair of electrodes, one of which is provided with a plurality of spark gaps.

30 A still further object of the invention resides in providing an insulated core in which the gapped electrode is partially embedded and a still further object resides in providing a plug which is simple in construction, cheaply manufactured and extremely effective in operation.

35 With these and other objects in view, my invention consists in the novel features of construction, combination and arrangement of parts as will be hereinafter referred to and more particularly pointed out in the specification and claims.

40 In the accompanying drawing forming a part of this application, Figure 1 is a side elevation of the plug. Fig. 2 is a vertical section therethrough. Fig. 3 is a transverse section as seen on line 3-3, Fig. 1, and, Fig. 4 is a vertical section showing a slightly 45 modified form of plug.

45 In carrying out my invention, I shall refer to the drawing in which similar reference characters designate corresponding parts throughout the several views and in which 1 indicates 50 a nut or shell having the lower portion externally threaded and adapted to be entered into a cylinder of an engine, the inner periphery of said nut being reduced in diameter toward one end thereof, and extending 55 therethrough is a core 2 formed of any de-

sired insulated material such as mica or porcelain. The insulated core 2 is tapered coincident to the tapering of the inner periphery of the nut 1 and is provided with a central channel 3 through which extends a 60 terminal or electrode 4, said electrode or terminal being provided on its one end with a head 5, while the opposite end thereof is threaded, as shown at 6, to receive a nut or the like 7, thereby retaining the same in position in the core. As stated, this member 4 which extends through the core 2 is a terminal or electrode and may be formed of any desired material which is a good electric conductor and the other electrode comprises a platinum wire 8 which is mounted in the lower end of the nut 1, as shown at 9, said wire being then brought down and embedded in a substantially annular groove 10 in the outer periphery of the core 2 adjacent its lower end. The groove 10 is extremely shallow in depth, being just sufficient to allow the wire to fit substantially flush with the outer wall of the core and the end of the wire opposite the grounded 70 end is extended through a transverse channel 11 in said core to contact with the central terminal or electrode 4. That portion of the wire which is mounted in the annular groove 10 of the core is provided with a plurality of gaps or spaces, as shown at 12, I having shown in this instance seven, but it will be understood that any number may be provided which is entirely within the scope of the mechanic, and it will be seen that when the current is passed through the electrodes, sparks will be formed at each of the gaps shown, without more current being necessitated than is used for the provision of a single spark, as in the present spark plugs. 75

80 In Fig. 4, I have shown a slightly modified form of plug in which a shell 13 has the inner periphery thereof suddenly reduced to form an annular shoulder 14 which receives a similar annular shoulder 15 85 formed on the insulated core 16. A clamping nut 17 engages the upper end of the inner periphery of the shell and secures the same to the core, and said core is also provided with a central vertical channel 18 which extends through from the upper end to a point adjacent the lower end thereof. Mounted in the channel 18 is an electrode or terminal 19, the upper end of which is threaded to receive a nut 20, whereby the 90 95 100 105 110

same may be secured in position in the core. The other electrode in this form comprises a platinum wire 21 which has one end thereof grounded within the nut or shell 13 and is 5 embedded in a shallow groove 22 which extends vertically along one side of the core 16, said groove continuing around the lower convexed end 23 of said core to the opposite side of the same. As stated, this platinum 10 wire which forms the other electrode, is mounted in this groove and the end thereof opposite the grounded end, is extended through a transverse channel 24 to contact with the lower end of the central terminal 15 or electrode 19. This electrode, as in the other form, is so embedded in the core as to have the outer periphery thereof flush with the outer wall of the core and that portion of the same which is extended around the 20 convexed portion of the core is provided with a plurality of gaps or spaces 25, which as in the other form, are all very small in diameter.

Although not before stated, it will be here 25 noted that in the form disclosed in Fig. 4 of the drawing, a washer 26 is provided which is adapted to rest on the shoulder 14 within the sleeve or shell 13, one face of said washer being lined with asbestos. In this 30 manner the shoulder 15 may rest thereagainst as the same is properly positioned within said shell, thus forming an air and gas tight connection.

It is a well known fact that any resistance 35 in an electric current causes more volume without any more consumption of current and the more sparks that are provided in a gas engine, the more apt the same is to fire the charge in a cylinder, so that it will be 40 seen that my improved plug is adapted to provide additional sparks without the use of more current and will, therefore, ignite the mixture at all times. With an increased spark such as this plug provides, it will be 45 seen that an imperfect mixture will be ignited as well as perfect one, thereby eliminating the chances of the motor "missing" and thus increase the power of the engine considerably.

50 It will further be seen that my improved plug is of such simple construction as to be readily and cheaply manufactured and one which is extremely effective in operation.

It must also here be stated that the spark

gaps in both forms are each of the same 55 width or size and the parts of the electrode inserted therebetween are so firmly held that the relative distance between the same cannot change when said electrode is heated. In this manner when the electrical connection is made with the one electrode, a substantial arc of fire will be formed about the core, the spaces between said gaps remaining the same throughout, thus giving a perfect spark and preventing the "missing" 65 which is so prevalent in the engines of today.

What I claim is:—

1. A spark plug comprising in combination a shell, an insulated core extending therethrough and provided with a hole therein and a groove on the end portion thereof, a conductor disposed in said groove and consisting of a plurality of segments spaced apart so as to give a series of spark-gaps in the conductor, one end portion of said conductor being connected to said shell, another conductor disposed in said hole and having one end portion adapted for holding a conducting wire thereto, a member secured to the end portion of the last mentioned conductor so as to bring the same into sparking distance with said segments. 75

2. A spark plug comprising in combination a shell, an insulated core extending therethrough, and provided with a hole 85 therein and provided with a groove on the end portion thereof, the core being provided with an aperture connecting said groove and said hole, a conductor disposed in said hole and having one of its end portions terminated therein, a nut provided on the other end of said conductor for securing a conducting wire or the like thereto, another conductor secured to said shell at one end, and having its central portion disposed in 90 said groove and said aperture, the portion in said groove consisting of a plurality of segments spaced apart so as to give a series of spark gaps in the conductor, the end of said conductor being secured to the first 95 mentioned conductor.

In testimony whereof I hereunto affix my signature in the presence of two witnesses.

JAMES W. NANCE.
